UNITED STATES PATENT OFFICE.

LOUIS P. DESTRIBATS, OF TRENTON, NEW JERSEY, ASSIGNOR TO AJAX RUBBER COMPANY, INC., OF MILBROOK, NEW YORK, A CORPORATION OF NEW YORK.

DESIGN FOR A TIRE-CASING.

52,430.

Specification for Design.

Patented Sept. 17, 1918.

Application filed April 10, 1917. Serial No. 161,081. Term of patent 14 years.

To all whom it may concern:

Be it known that I, LOUIS P. DESTRIBATS, a citizen of France, and resident of Trenton, in the county of Mercer and State of New Jersey, have invented a new, original, and ornamental Design for a Tire-Casing, of which the following is a specification, reference being had to the accompanying drawing, forming part thereof.

My new design for a tire casing is shown in the accompanying drawing, in which—

Figure 1 represents a plan view of a portion of a tire tread,

Fig. 2 represents a detail transverse section of the same, and

Fig. 3 represents a detail side elevation of the same.

I claim:

The ornamental design for a tire casing, substantially as shown.

LOUIS P. DESTRIBATS.
